UNITED STATES PATENT OFFICE.

JOHN L. SOMMER AND BERNARD BIEHL, SR., OF NEWARK, NEW JERSEY, ASSIGNEES TO
J. L. SOMMER MANUFACTURING CO., A CORPORATION OF NEW JERSEY.

SHOE-TREE.

Application filed March 15, 1923. Serial No. 625,205.

This invention relates in general to a shoe tree having the toe member formed of two relatively movable sections, one object of the invention being to provide novel, improved and simple means for actuating said toe sections relatively to each other to separate the said sections when the tree is placed into a shoe and to draw said sections together when the tree is removed from a shoe.

Another object is to provide such a shoe tree having a toe member spreading device including cooperating members one fixedly carried by each toe section and each having a slot or recess arranged longitudinally diagonal of the corresponding toe section and at an angle to the slot or recess in the other member, and an actuating device pivotally and slidably mounted in said slots or recesses and connected to the stretching toggle, whereby movement of said actuating device longitudinally of said toe sections causes the toe sections to move toward and from each other.

Further objects are to provide a novel and improved quickly adjustable stretching toggle, and to obtain other results and advantages as may be brought out by the following description.

Referring to the accompanying drawings in which the same reference characters designate corresponding and like parts,

Figure 1 is a side elevation of a shoe tree embodying our invention;

Figure 2 is a longitudinal vertical sectional view through the same, taken on the line 2—2 of Fig. 3;

Figure 3 is a top plan view of a shoe tree with the sections of the toe member separated;

Figure 4 is a top plan view of the shoe tree with the sections of the toe member together and showing the manner of adjusting the stretching toggle;

Figure 5 is a bottom plan view of the shoe tree with the sections of the toe member separated, portions being broken away for clearness in illustration;

Figure 6 is a transverse vertical sectional view, taken on the line 6—6 of Fig. 2;

Figure 7 is a detached perspective view of one of the spreading plates;

Figure 8 is a transverse sectional view through the stretching toggle, taken on the line 8—8 of Fig. 3;

Figure 9 is a similar view, taken on the line 9—9 of Fig. 4;

Figure 10 is an enlarged fragmentary side elevation of one of the links of the stretching toggle showing the adjusting stud in operative position, and

Figure 11 is a similar view showing the adjusting stud in the position assumed when adjusting the length of the toggle.

In the specific embodiment of the invention shown on the drawings the reference character A designates the toe member of the shoe tree which is longitudinally divided into two sections 1 and 2 preferably formed of wood, said toe member being connected by a stretching toggle B to a heel member C.

Each of the toe sections 1 and 2 carries a spreading member or plate 3 which are shown as fixedly mounted in recesses 4 formed in the adjacent faces of the toe sections, the plates being connected to the toe sections by means of pins or the like 5. No movement of these plates 3, each with respect to its toe section, is required by my improved construction as hereinafter described, and thus they are made tight or in fixed relation to the toe sections.

The said plates 3 project laterally from the adjacent faces of the toe sections 1 and 2 in overlapping relation, as clearly shown in Figures 2, 3 and 6, and are connected at one end by a pin and slot connection 6 whereby movement of the plates toward and away from each other and relative longitudinal movement thereof are positively limited. Each of the plates 3 is provided adjacent its other end and its outer edge with a slot 7 arranged longitudinally diagonal of the corresponding toe section, said slots normally overlying each other.

An actuating device is slidably and pivotally connected to said plates 3, said actuating device comprising a slide 8, preferably formed of sheet metal with its edges turned upwardly and having a pin 9 mounted therein and extending through the slots 7, the said pin being provided at its ends with heads to permanently connect the actuating device to the plates 3.

The said actuating device is pivotally connected to one end of a link 10 which is arranged between the upturned edges of the slide 8 by means of a pivot pin 11 passing through said upturned edges or ears of the

slide and the link 10. The said link forms one part of the stretching toggle B and is pivotally connected at its other end to one end of another link 12 by means of a pin 13 rigidly connected to the link 10 and passing through a slot 14 in the link 12. The other end of the link 12 carries the heel member C which may be in the form of a substantially spherical block of wood or the like.

10 With this construction movement of the slide 8 and pin 9, constituting the actuating device, longitudinally of the toe member causes the toe sections 1 and 2 to be moved toward or from each other according to 15 the direction of movement of the actuating device through the engagement of the pin 9 with the slots 7. Thus, the toe sections 1 and 2 may be separated as the shoe tree is placed in a shoe, and the pivot pin 9 permits the toe sections to adjust themselves 20 to conform to the interior walls of the toe portion of the shoe. When the shoe tree is withdrawn from a shoe the toe sections are drawn toward each other to permit easy 25 removal of the tree. It will be noted that the separating of the toe sections takes place simultaneously with the extension of the stretching toggle B so that the shoe is simultaneously stretched both longitudinally and 30 laterally. During the separating and drawing together of the toe sections 1 and 2 the plates 3 slide upon one another so as to reinforce the spreading device and prevent the same from becoming bent or twisted 35 during the stretching operation. The adjacent faces of the toe sections are recessed as at 15 to receive the edges of the opposite plate 3 and the actuating device when the toe sections are drawn together. The outer 40 end of the link 10 is formed with the usual finger piece 16 for actuating the toggle and locking the same with the shoe tree in a shoe.

The invention also contemplates an improved adjusting means for the stretching toggle B. Said adjusting means is shown on the drawings as comprising an adjusting stud 17 rigidly connected at one end to one end of a spring strip 18 the other end 45 of which is rigidly connected to the pivot stud 17, the said stud 17 projecting through a slot 19 in the link 12 which comprises a plurality of substantially circular openings 20 connected by narrower slots 21. The 50 inner portion of the stud 17 is substantially circular in cross-section and of a diameter slightly less than the diameter of the openings 20, as indicated at 24, while the outer end of the stud is cut away at opposite sides 55 as at 22 to leave a neck 23 of a thickness slightly less than the width of the slots 21. The extremity of the stud is provided with a finger piece 25.

The spring strip 18 normally holds the 60 stud in such a position that the cylindrical

portion 24 is positioned in one of the openings. Longitudinal relative movement of the links 10 and 12 of the stretching toggle is thus prevented. When it is desired to adjust the length of the toggle B, the stud 17 is pressed by the finger of the operator against the action of the spring 18 to remove the cylindrical portion 24 from the opening 20 and produce registry of the flat neck with the slot 21, as indicated in Figures 4, 9 and 11. The links 10 and 12 are then forcibly moved by the operator in the proper direction until the length of the toggle is that desired, whereupon the stud 17 is released and the spring 18 returns the cylindrical portion 24 into another of the openings 20. It will be noted that the pivot pin 13 serves both as a pivot for the links 10 and 12 and also as a guide for longitudinal adjustment of said links, the slot 14 permitting the link 12 to slide relatively to the link 10.

While we have shown and described the toe member of the shoe tree as formed of wood with metal plates 3 rigidly connected thereto, it will be understood that it is within the scope of the invention to form the slots 7 directly in the shoe tree or a projecting portion thereof corresponding to the plates 3, and the toe portion may be formed of other suitable material than wood; also, the details of construction of the actuating device and the adjusting means for the stretching toggle may be modified by those skilled in the art without departing from the spirit or scope of the invention. Therefore, we do not desire to be understood as limiting ourselves except as required by the following claims when construed in the light of the prior art.

Having thus described the invention, what we claim is:

1. A shoe tree including a pair of toe sections each having a portion fixed against motion with respect to its section, such fixed portions overlapping each other and having slideways in their overlapping portions each longitudinally diagonal of its toe section and oppositely disposed from the other so that said slideways cross each other, and an actuating device slidably mounted in said slideways at their point of crossing so that as it moves longitudinally of the sections it moves said fixed portions toward and from each other to adjust the toe sections.

2. A shoe tree including a pair of toe sections each having a portion fixed against motion with respect to its section and overlapping a corresponding fixed portion of the other section, said overlapping portions having oppositely disposed slideways arranged longitudinally diagonal of the respective toe sections and crossing each other, a member slidably mounted in said slideways at their point of crossing, and means for sliding said

member when the tree is in a shoe or the like.

3. A shoe tree including a pair of toe sections each having a portion fixed against motion with respect to its section, such fixed portions overlapping each other and having slots in their overlapping portions each longitudinally diagonal of its toe section and oppositely disposed from the other so that said slots cross each other, and an actuating device slidably mounted in said slots at their point of crossing so that as it moves longitudinally of the sections it moves said fixed portions toward and from each other to adjust the toe sections.

4. A shoe tree including a pair of toe sections each having a portion fixed against motion with respect to its section and overlapping a corresponding fixed portion of the other section, said overlapping portions having oppositely disposed slots arranged longitudinally diagonal of the respective toe sections and crossing each other, a member slidably mounted in said slots at their point of crossing, and means for sliding said member when the tree is in a shoe or the like.

5. A shoe tree including a pair of toe sections each having a portion fixed against motion with respect to its section and overlapping a corresponding fixed portion of the other section, said overlapping portions having oppositely disposed slots arranged longitudinally diagonal of the respective toe sections and crossing each other, and an actuating device including a slide carrying a pin slidably mounted in said slots at their point of crossing to move said fixed portions toward and from each other to adjust the toe sections.

6. A shoe tree including a pair of toe sections, plates embedded at their edge portions one in each of the adjacent faces of said toe sections in fixed relation thereto, said plates having projecting portions overlapping each other and having slideways oppositely oblique to the length of the toe sections, and an actuating device slidably mounted in said slideways to move said plates toward and from each other to adjust the toe sections.

7. A shoe tree including a pair of toe sections each having a recess formed in its face adjacent the other section, plates secured one in each of said recesses in fixed relation thereto and projecting therefrom, the projecting portions of said plates overlapping and having slideways oppositely oblique to the length of the toe sections, and an actuating device slidably mounted in said slideways to move said plates toward and from each other to adjust the toe sections.

8. A shoe tree including a pair of toe sections having fixed portions overlapping each other and slideways in said overlapping portions each longitudinally diagonal of its toe section and oppositely disposed from the other so that said slideways cross

each other, an actuating device slidably mounted in said slideways at their point of crossing so that as it moves longitudinally of the sections it moves said fixed portions toward and from each other to adjust the toe sections, and a transverse extensible connection of said fixed portions for preventing relative longitudinal movement of said toe sections.

9. A shoe tree including a pair of toe sections having fixed portions overlapping each other and slideways in said overlapping portions each longitudinally diagonal of its toe section and oppositely disposed from the other so that said slideways cross each other, an actuating device slidably mounted in said slideways at their point of crossing so that as it moves longitudinally of the sections it moves said fixed portions toward and from each other to adjust the toe sections, and a transverse slot and pin connection of said fixed portions for preventing relative longitudinal movement of said toe sections.

10. In a shoe tree having a toe member and a heel member, a pair of overlapping links one connected to said toe member and the other connected to said heel member, said links being hinged at their overlapping ends by a pivot stud on one link entering a longitudinal slot in the other link, and means for adjustably positioning the pivot stud in its slot consisting of an adjusting member mounted on the pivot stud link concentric with said stud and adapted to engage the other link at a distance from its slot to prevent relative longitudinal movement of the links.

11. In a shoe tree having a toe member and a heel member, a pair of overlapping links one connected to said toe member and the other connected to said heel member, said links being hinged at their overlapping ends by a pivot stud on one link entering a longitudinal slot in the other link, and means for adjustably positioning the pivot stud in its slot consisting of an adjusting member mounted on said pivot stud and adapted to engage the other link at a distance from its slot to prevent relative longitudinal movement of the links.

12. In a shoe tree having a toe member and a heel member, a pair of overlapping links one connected to said toe member and the other connected to said heel member, said links being hinged at their overlapping ends by a pivot stud on one link entering a longitudinal slot in the other link, and a resilient adjusting member mounted in the pivot stud link concentric with said stud and normally engaging the slotted member intermediate its slot and shoe-engaging member to prevent relative longitudinal movement of the links.

13. A shoe tree including a toe member,

a heel member, a pair of overlapping links one connected to said toe member and the other connected to said heel member, one of said links having a longitudinal slot and the 5 other carrying a pivot stud arranged in said slot, the slotted link also having a plurality of longitudinally spaced openings, a spring

strip connected at one end to said pivot stud and overlying said slotted link, and an adjusting stud mounted at the other end of 10 said spring strip and adapted to project through any of said spaced openings.
